INVENTOR

Andrew M. Robinson.

BY

Howard E. Barlow

ATTORNEY

UNITED STATES PATENT OFFICE.

ANDREW M. ROBINSON, OF PROVIDENCE, RHODE ISLAND, ASSIGNOR TO R. I. ELECTRICAL INSTRUMENT CO., OF PROVIDENCE, RHODE ISLAND, A CORPORATION OF RHODE ISLAND.

ELECTRIC ENGRAVING APPARATUS.

1,289,000.

Specification of Letters Patent. Patented Dec. 24, 1918.

Application filed January 28, 1918. Serial No. 214,258.

To all whom it may concern:

Be it known that I, ANDREW M. ROBINSON, a citizen of the United States, and resident of the city of Providence, in the county of Providence and State of Rhode Island, have invented certain new and useful Improvements in Electric Engraving Apparatus, of which the following is a specification.

This invention relates to an electric engraving apparatus employed for graduating tools or otherwise marking metal parts, and the object of this invention is to provide such a marking apparatus with a transformer for producing the desired character of electric current to be applied to the work, a work-support and an engraving pencil all connected in a main electric circuit, whereby when the point of the pencil is moved along the surface of the work, the current in passing from the pencil through the work, scores or cuts the metal in the path traveled by the pencil.

A further object of the invention is to provide an auxiliary electric circuit also connected to the pencil and means in the pencil for controlling the making and breaking of the auxiliary circuit to open and close the main circuit, so as to prevent arcing at the pencil point when raised from the work, which arcing effect pits the work and is quite objectionable where fine quality of work is desired.

With these and other objects in view, the invention consists of certain novel features of construction, as will be more fully described, and particularly pointed out in the appended claims.

In the accompanying drawings:

Figure 1— is a perspective view of my improved engraving apparatus, showing the same as adapted to be contained within a single portable receptacle.

Fig. 2— is a diagrammatic view showing the general arrangement of the transformer and the switches for controlling the flow of current in the main circuit therefrom; also showing the auxiliary circuit as arranged to break the main circuit by operating means carried by the pencil.

Fig. 3— is a wiring diagram showing both the main and the auxiliary circuits.

Fig. 4— is a sectional side elevation showing a detail construction of one form of engraving pencil having means therein for making and breaking the main circuit at

will of the operator through an auxiliary circuit.

Referring to the drawings, 10 designates a portable receptacle which is preferably in box-form with a cover 11 hinged thereto at 12, the same being provided with a handle 13 by which the whole apparatus may be readily carried about in the hand of the operator, the cover being provided with suitable hooks (not shown) adapted to engage the pins 14 on the front of the box for locking the lid closed.

In this box is mounted a transformer 15 preferably of the usual variable type for changing the alternating to the direct and by which the intensity of this current may be nicely regulated.

Above this transformer I have placed a deck 16 in the casing on which is conveniently mounted the various switches by which the character or intensity of the current delivered to the engraving pencil and to the work may be easily controlled.

In this construction, switch 18 controls the heavy current while switch 19 controls the light current, which currents are arranged to flow from the transformer through wires 20 and 21 respectively and through wire 22 to the engraving pencil 23. The switches 24, 25, 26 and 27 are for the purpose of controlling four different intensities of current so that the one desired may be caused to flow from the transformer to the work platen 28 through the main circuit wire 29. By this arrangement when the lightest cut is desired on the work 30, or where the work itself offers the minimum resistance, switches 19 and 24 are the only ones that are closed, but when the heaviest cut is desired, or when the work offers the maximum resistance, switches 18 and 27 are the only switches closed, intermediate intensities being obtained through switches 25 and 26.

In some instances it is found particularly where the heavier current is used that upon raising the pencil from the work an electric arc is established, which pits or mars the work rendering it imperfect.

To obviate this difficulty, which is found to be quite objectionable where fine work is desired, I have provided a second circuit which is arranged to be opened and closed by means of the press button 31 in the pencil. This secondary circuit is arranged to control the primary circuit as follows:

The main current enters through wires 32 and 33. Wire 33 being connected through the contact points 34 and 35, armature 36 and wire 37.

5 In this auxiliary circuit is the battery 38 and electro-magnets 39, the wires of this circuit extending into this pencil and are connected, as illustrated in Fig. 3, to the contact points 40 and 41, whereby when the 10 button 31 is depressed the bridge-member 42 completes the circuit through the wires 43 and 44, energizes the magnets 39 to withdraw the armature 36 and so breaks the main circuit between the contacts 34 and 15 35. This breaking of the main circuit is done before the point of the pencil is raised from the work thus effectually preventing the arcing at the pencil point and injuring the work.

20 These circuit-breaking magnets and contact points 34 and 35 are preferably mounted in the small inclosing case member 45 which is secured to the main receptacle by screws 46 thus rendering this mechanism quite accessible and providing a unitary structure 25 capable of being readily carried about from place to place in the hand of the operator.

30 A plug 47 which may be readily connected to the source of electric energy is connected to wires 32 and 33 of the main circuit.

I do not wish to be restricted to the connecting of an auxiliary circuit to the pencil as in some instances this pencil may be operated quite satisfactorily without the use 35 of such auxiliary circuit when used in connection with the mechanism above described.

I claim:

1. An electric engraving apparatus comprising a main circuit, a work-support and 40 an engraving pencil in said circuit, an

auxiliary circuit, and means whereby said auxiliary circuit may be caused to break said main circuit when desired.

2. An electric engraving apparatus comprising a main circuit, a work-support and 45 an engraving pencil in said circuit, an auxiliary circuit, and means in said pencil whereby said main circuit may be broken through said auxiliary circuit.

3. An electric engraving apparatus comprising a portable receptacle inclosing an electric current transformer, a plurality of switches in said receptacle for controlling the intensity of the current to be applied to the work, a work-support of conducting 55 material, a conductor leading to said work support, an engraving pencil, a conductor leading to said pencil and a conductor adapted to be connected to the source of 60 electric supply.

4. An electric engraving apparatus comprising a portable receptacle in which is mounted a transformer for the main electric current and a plurality of switches for controlling the intensity of the current to 65 be applied to the work, a work-support electrically connected from said transformer through said switches, an electric engraving pencil electrically connected from said transformer, an auxiliary circuit, and means in said pencil whereby said latter circuit may be caused to either make or break the main circuit through said pencil and work-support.

In testimony whereof I affix my signature 75 in presence of two witnesses.

ANDREW M. ROBINSON.
